UNITED STATES PATENT OFFICE.

GEORGE W. MARSH, OF OAKLAND, CALIFORNIA.

COOLING DEVICE FOR AN ENGINE.

1,077,414.

Specification of Letters Patent.

Patented Nov. 4, 1913.

Application filed January 6, 1913. Serial No. 740,511.

To all whom it may concern:

Be it known that I, GEORGE W. MARSH, a citizen of the United States, residing at Oakland, in the county of Alameda and State of California, have invented certain new and useful Improvements in Cooling Device for an Engine, of which the following is a specification.

This invention relates to improvements in cooling systems for automobiles and has special reference to a device which is provided with a means for increasing the power of the engine and for preventing or removing deposits of carbon within the cylinder.

Another object of this invention is to construct a cooling means for the radiator thereby always maintaining a partial vacuum therein, whereby the boiling point of the water will be greatly lowered thereby keeping the engine in a cooled condition.

A still further object of this invention is the production of a device which is adapted to introduce a mixture of steam and air into the cylinder, the former preventing the deposition of carbon therein, while the latter increases the power of the engine by better combustion.

With these and other objects in view this invention consists in general of certain novel constructions, combinations and arrangement of parts as will be hereinafter fully described and claimed.

In the accompanying drawings: Figure 1, is a central longitudinal section of the forward portion of the engine. Fig. 2, is a central longitudinal section of the check valve used in combination with this device. Fig. 3, is a longitudinal section on the three-way valve used with this invention.

Referring to the accompanying drawing by numerals, it will be seen that the device consists of the ordinary engine 1 which is provided with a water jacket 2 and an exhaust 3. The engine is also provided with an inlet 4 which communicates with the carburetor 5 and the fuel intake member 6. In order to cool the engine there is provided the usual fan 7.

Mounted at the forward portion of the engine there is provided a radiator 8 which is connected with the water jacket 2 by means of the conduit 9. The conduit 9 extends from the upper portion of the water jacket 2 to the lower corner of the top member of the radiator 8, whereby the water level in the upper portion of the radiator 8

will be at a considerable distance from the top thereof. In order to fill the radiator 8 there is provided a filling neck 10 which is adapted to be closed by means of the threaded cap 11. It will further be noted, that the lower portion of the radiator 8 is provided with the return pipe 12 whereby to allow the water to circulate.

From the foregoing description it will be seen that the common engine is used in combination with this device.

The device or invention consists in general of the tube 13 which is provided with the upwardly curved portion 14, the upper end 70 of which extends up into the filling neck 10 so as to normally remain above the water level. The lower portion of this tube 13 is connected with the inlet 4 as illustrated at 15. Adjacent to the lower end of this tube 75 13 there is provided a valve casing 16 in which the check valve 17, is mounted. It will be seen that in the use of this check valve 17, the vapor or steam which is generated in the radiator 8 will be drawn into the 80 inlet 4, there mixing with the gases which are passing into the cylinder. Although the stroke of the cylinder produces sufficient suction to draw the steam through this check valve 17, it will, of course, be noted that 85 when the device is not in use it will be impossible for any of the gases to pass through the check valve. The tube 13 is also provided with a secondary valve casing 18 in which the three-way valve 19 is rotatably 90 mounted. This three-way valve 19 is provided with the stem 20 and the rod 21 whereby the same may be manually operated. The casing 18 is provided with the lower opening 22 in which the depending exhaust 23 is 95 mounted.

When the engine is running, the three-way valve is open, as illustrated in Fig. 3, so as to present a passage from the radiator to the inlet 4. Since the amount of vapor generated within the radiator 8 is considerably less than can be carried from it by the tube 13, the water jacket 2 is divided with stem 24 and the valve 25 which is adapted to allow a certain amount of air to be drawn through 105 the conduit 9 and into the radiator 8. As the air which is drawn through this conduit is drawn from without the engine the same will be of a cooler temperature whereby as the same passes through the water it will be 110 heated, and at the same time will lower the temperature of the water. After this air

passes through the water in the upper portion of the radiator 8, it will ascend into the filling neck 10 at which time it will pass down through the tube 13 owing to the suction therein. When it is not desired to use this device the stem 20 may be so moved by the rod 21 as to allow the forward portion of the secondary casing 18 to communicate with the exhaust 23 whereby the steam with- 10 in the radiator 8 may be carried off through the exhaust.

If it is desired to cleanse the cylinder of any carbon which may be contained therein, a quantity of volatile liquid may be poured 15 through the filling neck 10 and when the engine is started to run the vapor therefrom will pass into the cylinder, thereby cleansing the same. By detaching the rod 21 from the member 20, the member 20 may be swung 20 so as to allow the rear portion of the secondary casing 18 to communicate with the exhaust 23, when a can of kerosene may be placed upon the lower portion of the exhaust 23 whereby the suction within the cylinder 25 will be sufficient to draw a quantity of the same through the exhaust 23 and tube 13 into the inlet 4 and the cylinder whereby the same will be cleansed of any deposits of carbon which may be contained therein. It 30 will, of course, be understood that the air which is admitted through the valve 25 and stem 24 will aid the combustion while the steam which is carried off from the radiator 8 will tend to prevent any carbon from being 35 deposited within the cylinder.

Having thus described the invention what is claimed as new, is:—

1. In a cooling system for an automobile, the combination with a water jacket and a

cylinder of a gas engine, a radiator positioned contiguous to said water jacket, a conduit forming a communication between said water jacket and radiator, a carbureter provided with an inlet leading into said cylinder a tube provided with a check valve, said tube 45 also provided with a valve casing, a three-way valve mounted in said casing, an exhaust member carried by said casing and depending therefrom, said exhaust communicating with said three-way valve for allowing the vapor from said radiator to be exhausted when so desired, manually operating means connected to said three-way valve for operating the same, the vapor in said radiator adapted to pass through said tube, 50 valves, and inlet so as to enter the cylinder.

2. In a cooling system for an automobile, the combination with a water jacket and a cylinder of a gas engine, a radiator positioned adjacent said water jacket, a conduit 60 forming a communication between said water jacket and radiator, a carbureter provided with an inlet leading into said cylinder, a tube provided with a check valve and a manually operable valve constituting a 65 passage between said radiator and said inlet, said manually adjustable valve provided with an exhaust for discharging the vapor from said radiator, a stem extending from said manually operable valve, and an operating rod connected to said stem for operating said valve.

In testimony whereof I affix my signature in presence of two witnesses.

GEORGE W. MARSH.
